TELEPHONY.

1,105,346.

Specification of Letters Patent.

Patented July 28, 1914.

Application filed May 22, 1911. Serial No. 628,778.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems and particularly to that class of telephone exchange systems in which telephone lines are automatically extended, and my invention is of service in connection with those telephone exchange systems in which the selecting mechanism in any way takes part in effecting the extensions of the telephone lines, whether such extensions are in the form of called lines or are mere link connectors limited to location at the exchange.

My invention has for its object the provision of means whereby the selecting mechanism that performs the function or functions above mentioned may also be employed to apply ringing current to a calling party line whereby a call may be initiated at one station upon a party line and be received at any station upon the party line without the intervention of especially provided selecting mechanism such as has been hitherto employed for the sole purpose of applying ringing current to calling party lines. By means of my invention I am enabled to eliminate the especially provided selecting mechanism hitherto associated with party lines for the purpose mentioned.

The telephone line extending selecting mechanism is, in accordance with another feature of my invention, adapted selectively to connect sources of current of different character individually suited to signal receivers at the party line stations whereby any party line station may selectively signal any other party line station. By this feature of my invention code signals need not be employed, but I do not limit my invention to systems in which code signals are absent.

By means of my invention the selector switch operated by a calling party line operates to convey selected calling current from the selected source back upon the same line from which a call is being initiated whereby reverted calls may be effected with-

out employing connector switches between the selector switches and the line from which calls are being initiated.

I will explain my invention more fully by reference to the accompanying drawings showing an embodiment thereof in the form of an automatic telephone exchange system, and in which drawings—

Figure 1 shows a party telephone line with four stations connected therewith, and Fig. 2 shows the automatic exchange end of said party telephone line and automatically operated selecting mechanism for automatically effecting the extension of the party telephone line and also for connecting a source of ringing current with the party telephone line when the called station is on the same line with a calling station.

I will first describe, somewhat in detail, the particular party line station equipment illustrated in Fig. 1, it being understood that I do not limit myself, however, to the particular equipment shown. The telephone line extends from the exchange to two limbs 1, 2 and, in the embodiment of the invention illustrated, is normally connected at its two sides with the poles of a battery 3, the side 1 being grounded and connected through the ground to the positive pole of the battery 3, and the negative pole of the battery 3 being connected with the side 2 of the line. The current furnished by the battery 3 is preferably uni-directional. Mechanism is provided at the exchange for reversing the current applied to the line after a party at one of the telephone stations upon the line takes the line for use, the source of current 3, being itself then reversed so that the side 1 is charged from the negative pole of the battery and the side 2 is charged from the positive pole of the battery. The apparatus by which the battery 3 is reversed, and which is illustrated in Fig. 2, is familiar to those that are skilled in the art of automatic telephony and will be later more fully referred to.

I have shown four party line stations A B C D though I do not limit myself to the number of stations that are connected with the party line. As the invention is illustrated, the equipments at the four stations are identical except, if desired, the signal receivers at the different stations may be of harmonic type to respond to wave form current of different periodicities to be selectively impressed upon the line at the ex-

change. The signal receivers may be alike, if desired, in which event code signals should be employed.

Similar parts at the different stations will 5 be given similar characters of reference, one station being specifically described.

In the system illustrated, being an automatic telephone exchange system, I have 10 illustrated a well known type of switching mechanism at each telephone station for operating the selecting mechanism at the exchange.

In the embodiment of the invention illustrated, the switching mechanism is controlled by a well known dial mechanism that 15 includes a spring winding finger ring or dial 4. The lever 5 engaged by the finger at the limit of the dial stroke releases the spring actuated device that intermittently 20 operates the circuit opening switch 6 during the return of the spring actuated mechanism to normal.

It is not necessary to describe in further detail the switching mechanism that is employed to operate the selecting mechanism at 25 the exchange and furthermore, the invention is not to be limited to the particular type of switching mechanism illustrated. It should be said, however, that it is usual, where dial 30 mechanism is used, to employ a master switch including contacts 7 and 8, in conjunction with the switching device 6 and in serial relation therewith, this master switch being controlled by the switch hook 9. The 35 telephone receiver 10, when upon its switchhook operates to depress the element 8 of the master switch and there open the circuit through switch 6, through the intermediation of the depressing finger 11 and the right 40 hand end portion of the lever 12 then depressed by the finger 11, the right hand end portion of the lever 12 being mechanically connected with the switching element 8 by means of a strut 13. The switchhook, when 45 depressed causes pawl 11' to hold the dial. There is a low resistance bridge conductor at each telephone station that includes the telephone transmitter 14 having one terminal telephonically connected with the limb 50 1 of the telephone line, and the receiver 10 in serial relation with the transmitter 14, the dial switch 6, and the contacts 7 and 8.

The normally open connection which has just been traced between the sides of the telephone line is in parallel relation with another bridge conductor which is desirably of high resistance and is preferably normally open at the contacts 15, 16. This second bridge conductor includes a magnet 17 which 60 is preferably polarized, and the entire resistance of this second bridge conductor is preferably located in the magnet which may be wound, for example, to ten thousand ohms resistance. The armature of the polarized magnet 17 is preferably held in a predeter-

mined normal position by means of a spring 18 that normally locks the nose or angular extension 19 of the armature beneath the nose or angular extension 20 of the intermediate pivoted lever 12. A spring 21 normally presses the nose 20 against the nose 19. The contact element 16 is mechanically connected with the finger 11 so that said contact 16 is permitted to engage the contact 15 when the associated telephone receiver 10 at a calling station is removed from its hook, whereby the high resistance bridge conductor including the magnet 17 is closed whereupon current from the battery 3 is permitted initial flow over the line sides in a direction 75 that will enable the magnet 17 to respond and draw its armature 19 from engagement with the nose 20 of the lever 12 against the force of the spring 18 whereupon the spring 21 is permitted to swing the lever 12 in a 80 counter clockwise direction, the finger 11 having previously been raised owing to the removal of the telephone from its switchhook. The contacts 7 and 8 of the master switch are thereupon engaged, whereafter 90 the low resistance bridge conductor is intermittently broken at 6 in a manner which is well understood and for the purpose of operating the selecting mechanism at the exchange to extend the telephone line in a manner well known. The low resistance shunts at the stations permit of sufficient flow of current through the selecting mechanism at the exchange to enable such selecting mechanism to operate. The high resistance shunts 95 that include the magnets 17 do not permit of the diversion of sufficient current from the low resistance shunts to interfere with the control that the switching mechanism in such a low resistance shunt at a station 100 which has appropriated the line has over the selecting mechanism at the exchange.

It is of course understood that the electromagnet 17 is responsive only to the current that is initially impressed upon the line 110 owing to the normal connection of the battery 3 with said line, this magnet at other times maintaining the telephone bridge open. By mechanism which is well understood, and which will later be mentioned more fully, the battery 3 has its connections with the sides of the telephone line reversed so that the current impressed upon the line immediately after the line is taken for use is such that the magnets 17 will not respond thereto, whereby those stations upon the line that are late in seeking to take the line for use cannot appropriate the line owing to the fact that the lever 12 at any station later to seek appropriation of the line is locked by the armature of the magnet at such station, whereby the contacts 7 and 8 of the master switch cannot be engaged to close the gap in the low resistance bridge at this later station, which closure is essential to enable a 115 120 125 130

station to take a line for use, pawl 11¹ then locking the dial. While current at any station at any time may be permitted to flow through the magnet 17 at such station, yet such magnet will not respond if the battery 3 has been reversed since the magnet will then be so energized as merely to tend to move its armature in the same direction in which such armature is pulled by the spring 18 without effecting readjustment of the parts that enter into the control of the receiver circuit and the control of the switching mechanism that governs the operation of the selecting mechanism. I therefore speak of the magnet 17 as being unresponsive to current that is caused to flow over the telephone line in a direction opposite to the normal flow of the current. The signal receiver 22 responds to wave form current that is preferably an alternating current and is operated in a manner which is well understood.

I have described the operation of the equipment at a single telephone station in detail under the assumption that such a station is a calling station, and under such assumption the battery 3 is immediately reversed after the line has been taken for use. When any of the stations upon the line is a called station, the battery 3 should have its normal connection with the telephone line preserved, at least until the called station has responded in order that the magnet 17 at the called station may respond to permit the closure of the contacts 7 and 8 thereat and thereby enable the inclusion of the telephone equipment at the called station in bridge of the telephone line.

Referring now more particularly to Fig. 2, the battery 3 has its negative pole normally connected with the side 2 of the telephone line through an energizing winding 23, the switch spring 24 and the normal contact of such spring. The positive pole of the battery 3 is connected with the side 1 of the telephone line through ground and the switch spring 25 and its normal contact. When the telephone line is taken for use by a calling party at one of the stations, circuit for the battery 3 is closed at the contacts 15, 16 at that telephone station, whereupon magnet 17 at such stations is operated with results which have been described. Later, the contacts 7 and 8 at the line appropriating station are engaged to close the low resistance shunt at such appropriating station, whereupon current from the battery 3 is increased sufficiently to energize the winding 23 (this winding not having been previously operatively energized owing to the presence of the high resistance magnet 17 in circuit therewith) to cause the armature 26 to be attracted. The armature 26, in being attracted, pushes the contact 27 into engagement with the normal contact of the switch

spring 25, thereby to bring the energizing winding 23 into a closed local circuit that may be traced from the grounded normal contact of the switch spring 25 through the winding 23 to the grounded battery 3 by the path marked "open main bat." when the master switch is at rest, whereby the armatures 29 and 30 are attracted with the result that the battery 3 has its connections with the sides of the telephone line reversed, these connections being then traceable from the side 1 of the telephone line, the contacts 31 that are closed by the armature 30, a winding of magnet 36, to the negative side of the battery 3 illustrated at the right of Fig. 2 (the illustration of the battery 3 being repeated seven times for sake of clearness) thence to the positive pole of the battery which is connected with the side 2 of the telephone line through the contacts 32 closed by the armature 30. The battery 3 is thus reversed instantly upon the closure of the contacts 7 and 8 at a calling station with the results which have been described. This association of the battery and telephone line is preserved during the time the receiver at the calling station is free of its hook, assuming the called station to be upon another line, owing to the establishment of a locking circuit through the locking winding 33. This locking circuit may be traced from the contacts 34 (closed as a consequence of the operation of the armature 35 of the magnet 36 included in the circuit of the battery 3 last traced, the subsequent energization of the magnet 37 controlling the contacts 34) through the contacts 38 closed by the armature 30, locking winding 33, the battery 3 and the ground that connects the battery with the contacts 34.

The equipment thus far described contains novel characteristics forming the subject matter of my co-pending application Serial No. 628,777, filed May 22, 1911, but it is to be understood that while I prefer the equipment just described, I do not limit myself thereto.

Having thus somewhat fully described a telephone exchange system in connection with which my invention may be practised, I will now specifically describe the characteristics of my invention as they are preferably embodied. Each party line station low resistance bridge conductor includes a key 39 adapted when depressed to introduce a resistance 40, which may be of three thousand ohms, in what was previously the low resistance bridge conductor, for the purpose of sufficiently reducing the current flow therethrough and as a consequence causing the inclusion of ringing current in circuit with the party line to enable one station upon such line to call another station as will later appear.

Referring now more particularly to Fig. 130

2, I have employed the first selector, indicated at the middle of the figure, for enabling the application of calling current to a calling party line, but it is to be understood that I do not limit myself to any particular switching mechanism entering into the line extending selecting mechanism for including the calling party line in circuit relation with a source of current, nor do I limit myself to the transfer of ringing current over the talking sides of the party line. The selector shown in Fig. 2 is of a type which is well known by those skilled in the art and is a form of mechanism that is installed by the Automatic Electric Company. As is well known, this selector has wipers which swing in horizontal planes and which are vertically adjustable so as to move in different levels, bank or waiting contacts being located in these levels which are connected with conductors that extend to connectors directly or through the intermediation of other selectors, whereby called lines are automatically connected with calling lines. The wipers of the selector shown in Fig. 2 are marked 41, 42 and 43 and these wipers are caused to swing in the selected level to suit the connection that they are to effect. One or more of the levels in which these wipers move includes bank contacts that are associated with sources of current.

In the embodiment of the invention illustrated code signaling is not employed, the signal receivers at the party line stations being responsive to currents of different character. For example, the signal receiver 22 at station A may respond to alternating current of sixteen cycles, the signal receiver at station B may respond to alternating current of thirty-three cycles, the signal receiver at station C may respond to alternating current of fifty cycles, and the signal receiver at station D may respond to alternating current of sixty-six cycles. If the invention is thus to be embodied, that is if the signal receivers are to be responsive to currents of different character, then there should be a plurality of levels of waiting or bank contacts associated with sources of ringing current of different character, the contacts in each of these levels being separately connected with a plurality of generators producing current of similar character so that some generator producing current of desired character may be available to enable a calling party line station to signal another station upon the same line. In Fig. 2 I have illustrated but one set of waiting contacts 41¹, 42¹ and 43¹ in one level, a single set of waiting contacts 41², 42² and 43² in the next level, a single group of contacts 41³, 42³ and 43³ in the next level, and a single group of contacts 41⁴, 42⁴ and 43⁴ in the next level. I have shown but one generator 44 in connection with the level containing the contacts

41¹, 42¹ and 43¹, it being understood that other groups of waiting contacts in this level are similarly associated with similar generators 44. I have not illustrated any equipment in association with the bank contacts of the remaining levels, it being understood, in the embodiment of the invention illustrated, that the generators associated with the first level produce alternating current of sixteen cycles, the generators associated with the contacts of the next level producing alternating current of thirty-three cycles, the generators associated with the contacts of the next level producing alternating current of fifty cycles, and the generators associated with the contacts of the next level producing alternating current of sixty-six cycles.

The calling party line party may select the level containing the waiting contacts that are associated with the calling generators producing current of the frequency or other character suited to the operation of the signal receiver 22 at the station upon the party line that is to be called. Having caused the wipers 41, 42 and 43 to occupy the desired level, these wipers are stepped around until waiting contacts associated with an unemployed generator 44 are encountered, the mechanism and circuits by which idle waiting contacts are engaged and busy waiting contacts are passed over being so well known as not to require explanation. It is assumed, for example, that any of the stations B, C, D is a calling party line station and that station A is the party line station upon the same line to be called. The calling station, in such case, selects the level containing the bank contacts 41¹, 42¹ and 43¹ and it is assumed that these contacts which are illustrated in Fig. 2 were previously free for selection and are engaged by the wipers 41, 42 and 43 for the purpose of associating the generator 44, previously unemployed, with the party line. The wipers stopping upon these waiting contacts cause the establishment of a circuit through the relays 45 and 46 and the reinclusion of the battery 3 in its normal circuit relation with the party line in which the side 1 is connected with the positive pole of the battery and the side 2 is connected with the negative pole of the battery in order to enable the party at the called party line station to bring his telephone into circuit relation with the party line.

The source of ringing current 44 has terminals in the form of the alternate contacts of armature switches of the ringing magnet 47, whose circuit includes a switch 48 periodically closed and opened by a revolving cam 49. The circuit of the ringing magnet 47 also includes a switch 50 that is closed through the agency of the armature switch of the relay 46 and the magnet 51 in direct association with the switch 50. The switch 50 is maintained closed during the time the

telephone bridge at the calling party line station is closed whether such bridge includes the resistance 40 or does not include such resistance, the relay 46 being suitably adjusted for this purpose. The relay 45, however, is adjusted to drop its armature when the resistance 40 at a calling party line station is included in the telephone bridge, whereby the circuit previously established through the relay 52 is opened and the switch 53 controlled by the relay 52 is closed. The switch 53 is thus adapted to be operated by the manipulation of the key 39 at a calling party line station to close the circuit of the ringing magnet 47 at one point, the point 53, as often as the calling party desires. The cam 49 operates to open and close the circuit of the ringing magnet 47 at the point 48 so that during the time the key 39 at the calling station is depressed the circuit of the magnet 47 is intermittently opened and closed, whereby the selected calling generator 44 is intermittently included in circuit with and excluded from the circuit of the party line.

During the time that the generator is upon the line, the armature switches of the magnet 47 are removed from their normal contacts so that the circuit of the relay 46 is then open. The switch 50 is maintained closed, however, owing to the establishment of an alternate circuit for the relay 51 which may be traced from the grounded battery 3 through the winding of the relay 51 to the uppermost armature switch of the magnet 47 and the grounded contact then engaged by said uppermost armature switch. As the invention is illustrated, the called party cannot secure telephonic connection with the party line until the battery 3 is again included in its normal circuit relation with the line, which condition occurs when the circuit through the ringing magnet 47 is opened at 48. I, however, do not limit myself to this characteristic which is simply preferred for engineering reasons. When the called party responds, a low resistance bridge is established across the sides of the party line through the telephone at the called party line station, whereby the magnet 45 is energized and the magnet 52 is consequently energized in order to open the circuit of the ringing magnet 47 at 53 during the presence of the low resistance shunt across the line at the called station or at the calling station under the assumption that the calling party has released his key 39. Thus the generator 44 is removed from circuit relation with the line after the called party has responded or the calling party has excluded the resistance 40 from his telephone bridge.

In passing it should be stated, in connection with the embodiment of the invention illustrated, that the calling party keeps his key 39 depressed during the interval in which

he expects the called party to respond in order that the telephone bridge at the calling station may include the resistance 40 for the purpose of enabling sufficient current to pass through the magnet 17 at the called station. When the relay 46 is energized, circuit is closed through the magnet 54 by way of the grounded armature switch of the relay 46 and the contact of such switch then engaged, the winding of the relay 54 to the grounded battery 3. When the ringing current is applied to the party line circuit for the relay 54 is closed through the uppermost armature switch of the magnet 47, the winding of the relay 54 and the grounded battery 3. The armature of relay 54 is thus constantly attracted so as to place a guarding potential or condition upon the contact 41¹ to prevent another calling line station from appropriating the contacts 42¹, 43¹ that are in service. This guarding potential also prevents the selector and associated switches from releasing in the manner well known.

The prior art is exemplified by British Patent 1298 of 1910.

While I have herein shown and particularly described the preferred form of one embodiment of my invention, I do not, as hitherto pointed out, wish to be limited to the characteristics specifically set forth as changes and other adaptations may be made without departing from the spirit of my invention.

Having thus described my invention, I claim as new and desire to secure by Letters Patent the following:

1. A telephone exchange system including a party telephone line connecting a plurality of party telephone line stations with an exchange, said telephone stations having signal receivers responsive to currents of differing character; selecting mechanism at the exchange and operable by the equipment at any of said party telephone line stations, when calling, for extending said party telephone line into connection with other telephone lines; a plurality of sources of signaling current for supplying the signal receivers at the aforesaid telephone stations with current to which said signal receivers are responsive; and means governed at any of said telephone stations, when calling, for causing said selecting mechanism selectively to connect that one of said sources of signaling current with said party telephone line which corresponds to the station upon said party telephone line that is to be signaled by the calling station upon the same line, said selecting mechanism serving to convey signaling current from the selected source to the selected party line station.

2. A telephone exchange system including a party telephone line connecting a plurality of party telephone line stations with an exchange, said telephone stations having sig-

6
nal receivers responsive to currents of differing character; selecting mechanism at the exchange and operable by the equipment at any of said party telephone line stations, 5 when calling; a plurality of sources of signaling current for supplying the signal receivers at the aforesaid telephone stations with current to which said signal receivers are responsive; and means governed at any 10 of said telephone stations, when calling, for causing said selecting mechanism selectively to connect that one of said sources of signaling current with said party telephone line

which corresponds to the station upon said party telephone line that is to be signaled by 15 the calling station upon the same line, said selecting mechanism serving to convey signaling current from the selected source to the selected party line station.

In witness whereof, I hereunto subscribe 20 my name this fourth day of May A. D., 1911.

MORTON L. JOHNSON.
